DESIGN FOR A STOOL PEDESTAL OR SIMILAR ARTICLE

Clement J. Thelander, Chicago, Ill., assignor to
The Chicago Hardware Foundry Company,
North Chicago, Ill., a corporation of Illinois

Application May 19, 1941, Serial No. 101,009

Term of patent 7 years

To all whom it may concern:

Be it known that I, Clement J. Thelander, a citizen of the United States and a resident of the city of Chicago, in the county of Cook and State of Illinois, have invented a new, original, and ornamental Design for a Stool Pedestal or Similar Article, of which the following is a specification, reference being had to the accompanying drawing, forming a part thereof.

In the drawing:

I claim:

The ornamental design for a stool pedestal or similar article, as shown.

CLEMENT J. THELANDER.
